(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is an enlarged front detail view thereof.

The outermost dashed broken lines in FIG. 1 show a display screen or portion thereof, and form no part of the claimed design.

The dot-dash broken lines in FIG. 1 and FIG. 2, and the area between the dot-dash broken lines and the solid line shown in gray masking in FIG. 1 show portions of the graphical user interface that form no part of the claimed design.
